Des. 185,614

PAGE 3

Fig. 1 is a top perspective view of a baby dish embodying my new design;

Fig. 2 is a bottom perspective view of the dish shown in Fig. 1;

Fig. 3 is a front elevational view of the dish shown in Fig. 1;

Fig. 4 is a top plan view of the dish shown in Fig. 1;

Fig. 5 is a side elevational view of the dish shown in Fig. 1; and

Fig. 6 is a bottom plan view of the dish shown in Fig. 1.

I claim:

The ornamental design for a baby dish or similar article, substantially as shown.
